LIGHTING FIXTURE

Louis Solomon, Brooklyn, N. Y.

Application April 18, 1936, Serial No. 75,106

1 Claim. (Cl. 240—78)

The invention relates to lighting fixtures and particularly to the kind known as ceiling fixtures. It has for its main object to produce a fixture which will give more light than the ordinary fixtures now in use, and which will diffuse this light more evenly.

Another object is to provide a lighting fixture which may be adjusted for various sizes of electric bulbs. A further object is to provide a lighting fixture which can easily be taken apart so that all the reflecting surfaces may be readily cleaned. A still further object is to provide a lighting fixture which will give no direct glare. Additional objects are to provide a lighting fixture of simple but pleasing appearance, which is easy to install, which may be used in outlets of various types, and which can be manufactured at a relatively low cost.

These and various other objects and advantages will be readily understood from the following description and from the accompanying drawing of preferred embodiments of the invention, in which, however, modifications may be made without departing from the scope of the appended claim. In the drawing

Fig. 1 is a cross-sectional elevation of the lighting fixture;

Fig. 2 is a cross-sectional elevation of a somewhat modified reflector used in the fixture;

Figs. 3 and 4 are fragmental plan views of the reflectors; and

Fig. 5 is a cross-sectional side view taken on line 5—5 in Fig. 3.

Referring now to the drawing, the device comprises a shade 10 which is secured to an electric attachment plug 11 in which the electric bulb 12 is inserted in the regular manner. The shade is formed with a parabolic part 13 near its upper end. Immediately below the shade flares out and has a curved surface 14, while the lower end of the shade is provided with a downwardly and outwardly flaring skirt 15. A parabolic reflector 16, which in this case is illustrated as made of glass and silvered on the inner face 17, is secured to the upper end 18 of the shade by means of a plurality of screws 19 which engage on a circumferential flange 20 formed on the upper end of the reflector.

As bulbs of various sizes may be used in this fixture, I provide a sleeve 21 which is telescopically mounted on the part 18 of the shade. This sleeve is provided with a plurality of slots 22 and with a plurality of screws 23 which are entered through the slots and threaded in bosses secured on the shade. The slots 22 enable the sleeve to be raised or lowered in relation to the shade so that the bulb may be in the right focal position in relation to the reflector 16.

The sleeve is secured to the attachment plug 11 by means of screws 24. In some instances I

prefer to use a globe 25 in combination with the fixture. The shape of such a globe is plainly shown in Fig. 1 and it is secured to the fixture by means of a plurality of screws 26 which are threaded in bosses secured on the shade. These screws engage on a flange 27 formed on the upper end of the globe. The lower part of the globe is preferably frosted so as to prevent direct glare.

While I have shown a reflector made of glass in Fig. 1, it is evident that metal reflectors, such as the one shown at 28 in Fig. 2, might be substituted. In fact in some cases it may be possible to use the inner surface of the part 13 of the shade as a reflector by plating this inner surface. However, in all the reflectors, whether made of glass or metal, it is preferable to make the reflecting surface undulated so that the rays impinging on the surface may be reflected in all directions. This may be done by forming a number of depressions, such as the diamond shaped depressions 29 shown in Figs. 3 and 5, or by making a number of circular depressions 30 in the reflector 16A, as shown in Fig. 4. In fact, undulations of any character may be employed to increase the efficiency of the reflector.

As the rays from the lamp impinge on the reflector they are bent in all directions by the undulations and reflected until they impinge upon the inner surface of the part 15 of the shade from which they are again reflected to light the place in which installed. Fixtures, constructed as here shown, have proved efficient in practice.

While I have shown the shade attached to a certain attachment plug it will, of course, be understood that it may be mounted on different forms of outlets, for example the shade might be connected directly to an outlet by having the screws of such outlet secured in the circumferential groove 31 formed in the sleeve 21.

Having described the invention and its objects, what I claim as new and wish to protect by Letters Patent is:—

A lighting fixture comprising in combination, a circular shade provided with an electric lamp 45 receptacle; a parabolic reflecting mirror contained in the upper part of the shade; a lamp inserted in the receptacle with its light source substantially coinciding with the focal point of the parabolic mirror; the reflecting surface of the mirror undulated to reflect rays in all directions; a downwardly-extending and outwardly-flaring metallic skirt, formed at the lower part of the fixture, below the electric lamp for reflecting rays from the lamp and for rereflecting 55 some of the rays from the undulated surface of the mirror; and a globe attached to the shade co-extensive with the reflecting skirt, and enclosing the electric lamp.
